UNITED STATES PATENT OFFICE

167,468

PORTABLE AIRPLANE HANGAR

John L. Mitchell, New York, N. Y., assignor to Mitchell Mobilhangar Corporation, New York,
 N. Y., a corporation of New York

Application March 5, 1949, Serial No. 1,226

Term of patent 14 years

(Cl. D13—1)

To all whom it may concern:

Be it known that I, John L. Mitchell, a citizen of the United States, residing in the county, city, and State of New York, have invented a new, original, and ornamental Design for a Portable Airplane Hangar, of which the following is a specification, reference being had to the accompanying drawings forming a part thereof.

In the drawings:

Fig. 1 is a top plan view of a portable airplane hangar showing my new design;

Fig. 2 is a side elevational view with the doors closed;

Fig. 3 is an end elevational view; and

Fig. 4 is a perspective view with the two triangular-shaped sections moved apart.

The dominant features of my design reside in the portions shown in full lines.

I claim:

The ornamental design for a portable airplane hangar, substantially as shown and described.
 JOHN L. MITCHELL.
